G. H. FAICHNEY.
WORK SUPPORTING TABLE.
APPLICATION FILED JAN. 23, 1920.

1,343,553.

Patented June 15, 1920.

UNITED STATES PATENT OFFICE.

GEORGE H. FAICHNEY, OF WATERTOWN, NEW YORK, ASSIGNOR TO THE RANDALL-FAICHNEY COMPANY, OF BOSTON, MASSACHUSETTS, A CORPORATION OF MASSACHUSETTS.

WORK-SUPPORTING TABLE.

1,343,553.

Specification of Letters Patent. Patented June 15, 1920.

Application filed January 23, 1920. Serial No. 353,433.

To all whom it may concern:

Be it known that I, GEORGE H. FAICHNEY, a citizen of the United States, residing at Watertown, in the county of Jefferson and State of New York, have invented certain new and useful Improvements in Work-Supporting Tables, of which the following is a specification.

This invention relates to improvements in work-supporting tables, and has for its object to provide a novel and simple device of the class designed especially for supporting a plurality of articles, while the latter are being operated upon. A further object is to provide novel means for holding the work during the operative periods, without the use of any extra clamping or securing means, and without danger of breaking or chafing the work, and whereby warped or otherwise distorted pieces of the work may be suitably supported while the operations are being effected. And a further object is to provide a work supporting member which is adjustable in various directions for positioning the several pieces of the work relatively to engraving or other tools.

I attain these objects by the means set forth in the detailed description which follows, and as illustrated by the accompanying drawings, in which—

Figure 1 is a top-plan view of the complete device and its supports; showing several pieces of work disposed and held in position to be operated upon. Fig. 2 is a vertical longitudinal section, taken on line 2—2 of Fig. 1; showing a number of engraving tools positioned above the work on the table. Fig. 3 is an enlarged fragmentary section, taken on the line 3—3 of Fig. 4. Fig. 4 is a similar view, taken on line 4—4 of Fig. 3; showing the Y-shaped grooves for receiving and holding the work. Fig. 5 is an enlarged broken plan-view; showing a warped or distorted thermometer disposed in one of the Y grooves. And Fig. 6 is a broken longitudinal section; showing another distorted thermometer supported by the Y groove.

The present application relates to a table which has been designed especially for supporting the well-known clinical and medical thermometers in common use by physicians, nurses and the like, while the said instruments are being engraved. These thermom-

eters are made of relatively small and delicate glass tubes, in which a very fine thread-like column of mercury is disposed. After the thermometers are filled and sealed, they are tested and then engraved for indicating the degree of temperature, the numbers by which the degrees are read, and the trademark and the name of the manufacturer and his place of business. The engraving is done by a well-known etching process by means of hydrochloric acid, and the first step in the engraving process consists of coating the entire glass body of each thermometer with a certain kind of wax, which is afterward inscribed by the use of sharp needle-like gravers, the needles cutting through the wax and exposing the surface of the glass where the etching is to be done. Following the engraving operations referred to, the thermometers are dipped in the acid, which completes the said work. In order to manufacture thermometers rapidly and economically, it is desirable to dip large numbers of the thermometers at a time, and to do this safely, the entire bodies of the tubes must be covered with the wax, so as to prevent the acid from coming into contact with portions of the tubes which are required to be free from blemishes. The handling of these wax-coated glass bodies during the engraving operations without chafing or marring the wax and accidentally exposing the glass, has always been a source of great trouble and annoyance. Heretofore, during the engraving operations, the machines employed for such work were invariably equipped with various clamping devices, which either gripped the ends or sides of the glass bodies, and as these devices were usually controlled by tension means, they required careful and frequent adjustment, in order to prevent the clamping members from chafing or biting through the wax coatings. But notwithstanding the exercise of such care, these older work-supporting devices caused considerable loss and waste of time and materials, and in addition rendered the manufacture of thermometers slow, as well as quite expensive. It is a particular object of the present invention to remedy all of the foregoing defects and to obviate the troubles and losses resulting therefrom in a novel and simple manner, and at the same time to greatly facilitate the production of

the clinical, as well as other thermometers. A detailed description of my improvement follows:

In the drawing, 2 represents a frame consisting of posts 3, which mark the four corners of the frame, and upon which is rigidly mounted similar rails 4, 4', the latter being held in place by screws 4". The rails are disposed parallel to and have rabbeted edges 4", which face each other. 5 designates a platform whose opposite ends are supported by the rabbeted edges of said rails, and said platform is adjustable longitudinally of the rails, by screws 6. 7 is the removable and adjustable table for supporting the work, which in the present case consists of a plurality of thermometers 8. The table 7 is preferably made of wood and lies flat upon the top face of the platform 5, preferably between similar cleats 5', which are rigid with the platform. By this arrangement, the table 7 may be adjusted longitudinally and horizontally by sliding on the platform, as shown by the dotted lines in Figs. 1 and 2, while both the table and the platform may be adjusted laterally by the screws 6. The table 7 is held in the operative position shown in the drawing entirely by gravity. The top face of the table 7 is provided with a plurality of longitudinal grooves 7', all of which are substantially Y-shaped in cross-section, as shown in Figs. 1, 4 and 5. These grooves are preferably parallel, and each is of suitable length to accommodate several of the relatively small thermometers 8 (see Figs. 1 and 2), during the engraving operations. As shown in Fig. 4, all of the thermometers 8 have their bottom sides 8' formed substantially V-shaped in cross-section. This is done for the purpose of magnifying the fine thread-like column of mercury, as well as the fine graduations, numbers, &c., to facilitate their accurate and plain reading. Owing to the fact that thermometers of this class are necessarily of small caliber, the difficulty heretofore experienced in holding the small glass bodies during the engraving operations is overcome in the present case, by disposing the V-shaped portions 8' in the Y-shaped grooves 7', whose sloping sides 7" conform to the V portions of the glass tubes, while the rounded top sides project slightly above the top surface of the table 7, where they may be freely engaged by the engraving needles, which are shown at 9, in Figs. 2 and 4. The smaller sizes of the thermometers when placed in the grooves 7' have their V-shaped edges 8' partially disposed in the narrow vertical legs 7" of the grooves. By this construction and arrangement of the table 7, the thermometers are snugly received by the grooves 7', and being somewhat assisted by gravity, are accordingly held firmly in place during the engraving operations. The table

7 being made of wood, which is less liable to chafe the wax coating of the thermometers, together with the Y-shaped grooves, which permit the thermometers to be applied like so many wedges, enables me to carry out the engraving operations rapidly and perfectly, without any danger of breaking the fragile tubes, or of chasing or peeling the wax, or otherwise spoiling or injuring the work. Furthermore, the arrangement of the grooves 7' is such that a relatively long and firm bearing is provided for each thermometer, as may be understood from Figs. 1, 2 and 3. The Y-shaped grooves also afford satisfactory means for holding the thermometers of the class which become warped or otherwise distorted during the making and tempering, as clearly shown in Figs. 5 and 6. In Fig. 5, the thermometer is shown to be warped laterally, at or near the end containing the mercury bulb 8", but owing to the flare of the upper portion of the groove 7', the distorted bulb 8" rests against one of the slanting sides of the groove, while the main body 8 is firmly seated in and held by the same groove, in the manner described. In Fig. 6 the thermometer body is bowed or bent upwardly. In this view the V-portion of the opposite ends of the body 8 are seated in the Y groove 7', which holds the body with sufficient firmness to prevent accidental movements during the engraving operation. The table 7 is employed in connection with multiple engraving machines, wherein the gravitational engraving tools 9 are used, and as these tools approach and engage the work supported by the table 7 entirely by gravity, they perform their work with the same facility and perfection, whether the thermometers are straight and true, or warped or bent, as shown and described. The grooves 7' being straight, they tend to hold the thermometers truly in the path of the gravers 9, and even where the glass tubes 8 are distorted, as shown, the symmetry, neatness and perfection of the engraving are maintained at all times.

Having thus described my invention, what I claim as new and desire to secure by Letters Patent, is—

115

1. In a work-supporting table, a rectangular plane body having a plurality of parallel Y-shaped grooves in its top face, a support for said body, means for guiding said body when moved longitudinally independent of said support, and means for adjusting said support for moving said body laterally in a horizontal plane.

120

2. A table for supporting thermometers during engraving operations, comprising a plane body having a plurality of longitudinal grooves in its top face, said grooves disposed parallel to each other, the bottom portions of said grooves having vertical walls, the top portions of said grooves being flared.

125

130

in opposite directions, and means for adjustably supporting said table.

3. A work-supporting table for engraving machines, comprising a plane body having a plurality of similar longitudinal grooves disposed parallel and being Y-shaped in cross-section, the oppositely flaring portions of said grooves adapted to conform to and provide seats for the V-shaped portions of 10 thermometers and like instruments, a frame for holding said body level, and means for adjusting said table for positioning the work in the path of engraving tools.

4. A table for supporting thermometers 15 during engraving operations, comprising a

plane body having a plurality of longitudinal furrows adapted to support the thermometers by gravity, the top portion of said furrows flaring in opposite directions laterally and adapted to engage V-shaped portions of the thermometers, the bottom portions of said furrows having perpendicular walls and adapted to afford clearance for the tips of said V-shaped portions, a support for said table, and means for adjusting said table for bringing the centers of said grooves within the path of the engraving tools.

In testimony whereof I affix my signature
GEORGE H. FAICHNEY.
